UNITED STATES PATENT OFFICE.

LARS MAGNUS ANDERSON AND AUGUST G. ANDERSON, OF ST. PAUL, MINNESOTA.

SAND-PACKING DEVICE USED IN FOUNDRY-MOLDING.

1,360,996.

Specification of Letters Patent.

Patented Dec. 7, 1920.

Application filed June 21, 1920. Serial No. 390,533.

To all whom it may concern:

Be it known that we, LARS M. ANDERSON and AUGUST G. ANDERSON, citizens of the United States, residing at St. Paul, county 5 of Ramsey, State of Minnesota, have invented an Improvement in Sand-Packung Devices Used in Foundry-Molding, of which the following description, in connection with the accompanying drawings, is a 10 specification, like characters on the drawing representing like parts.

This invention is particularly adapted for use in the formation of the usual sand molds in flasks employed in the molding art. At 15 present, there are three well-known methods in commercial use: one, in which the sand is placed in the flask and manually tamped; another, in which the sand is placed in the flask and the whole flask is vibrated; and 20 another, in which the sand is thrown into the flask by means of a rotating disk carrying a peripheral paddle. Hence, the idea of forcibly projecting the packing sand into the mold is not novel so far as this improvement 25 is concerned. This improved device provides means for projecting a steady, easily directible stream of sand into the flask and effects such result through the novel provision of two co-operable endless 30 conveyer members, one of which travels relatively to the other so that any sand lumps are reduced before being projected from the device into the flask. Furthermore, the device is so actuated that during 35 any given operation the molding sand is projected into the flask more forcibly toward the end of the operation than at the beginning.

The object, therefore, of this invention is 40 to provide a new and improved sand-packung device for foundry molding.

Other objects of the invention will more fully appear from the following description and the accompanying drawings and will 45 be pointed out in the annexed claims.

In the accompanying drawings, there is disclosed a structure designed to carry out the objects of the invention, but it is understood that the invention is not confined to 50 the exact features shown, as various changes may be made within the scope of the claims which follow.

In the drawings,

Figure 1 is a front elevation of the de- 55 vice;

Fig. 2 is a section on the line 2—2 of Fig. 1;

Fig. 3 is a side elevation of the device;

Fig. 4 is a section on the line 4—4 of Fig. 3;

Fig. 5 is a section on the line 5—5 of Fig. 1.

For the purpose of full disclosure of this invention, this selected embodiment thereof is shown and described. It consists broadly 65 of a sand-receiving hopper adapted to discharge the molding sand between two chute or conveyer members. While one of these members may be stationary and the other member moved relatively to the first-men- 70 tioned, so that the sand not only may be forcibly projected but also any lumps re-duced before projection therefrom, it is preferable to actuate both members, one 75 preferably traveling at a greater rate of speed than the other. Specifically, in this preferred construction, two endless, flexible belt conveyers are suitably mounted so as to present two adjacent opposed conveyer surfaces which travel in the same direction. 80 The conveyer members are adjustably mounted so that the interval between the opposed surfaces may be increased or di-minished as desired.

The device here shown comprises a hop- 85 per 1 preferably formed integrally with the frame 2 which extends below the hopper and is bifurcated to provide legs 3 and 4 between which are mounted, in suitable bearings, the shafts 5 and 6 of the upper 90 and lower pulleys 7 and 8 over which travels the conveyer member 9. Each of the two conveyer members consists prefer-ably of an endless, flexible belting, traveling 95 on pairs of pulleys.

This frame 2 of the device is adapted to be supported by means of arms 10 and 11. The terminal portion of the upper arm 10 is suitably secured within a boss 12 formed on the hopper portion of the frame, while 100 the lower arm 11 is similarly secured to a boss 13 on one of the frame legs. The other terminal portion of each of these arms 10 and 11 are secured within bosses 14 and 15 respectively presented by sleeves 16 and 17 carried by the standard 18.

The standard 18 also provides a con- 105 venient mounting for the means for the actuation of each of the driven pulley shafts 5 and 25, which is here diagrammatically 110

shown as an electric motor 19, the rotor of which drives a pulley through a suitable prolongation of its shaft. Two such electric motors 19 are preferably provided, one to 5 drive each of the shafts of the two upper pulleys 7 and 23 of the device. These motors are alike, similarly mounted on opposed sides of the standard 18 and, as the ordinary type may be employed which is capable of 10 working at various speeds, it is not deemed necessary to indicate two. While other driving means may be provided, it has been found that the provision of an individual motor for each upper pulley shaft is most 15 simple and effective as not only are the two pulleys and therefore conveyers preferably driven at different rates of speed, but also the linear rates of speed of the conveyers is increased as the particular flask is 20 being filled. This speed increase effects the more firm packing of the molding sand in the flask as the flask becomes filled.

In order that slack may be easily taken up in the endless conveyer, the lower end 25 of each frame leg is forked and a bearing-box 20 is adjustably supported therein. Adjustment of the bearing-box is attained by means of the screw 21.

The other conveyer member 22 travels 30 over the upper and lower pulleys 23 and 24. A bearing for the shaft 25 of the upper pulley 23 is provided by two bearing brackets 26, one on each side of the pulley. This shaft 25 is shown in Fig. 3, as broken, and 35 its prolongation actuatable by the motor 19. Each bracket 26 is secured by bolts 27 to one of the projecting flanges 28 of the frame adjacent the hopper. In order that the upper pulley 23 may be adjusted toward and from 40 the upper pulley 7, the flanges 28 are provided with elongated apertures or slots so that the brackets may be adjustably positioned within the permissive limits of the elongated slots 30 in the flanges through 45 which are passed the bolts 27. Nuts 31 on the bolts maintain the brackets in positioned relation to the flanges 28.

In this preferred construction the four 50 pulleys are so mounted that the adjacently presented working surfaces of the two conveyers are downwardly inclined toward each other. In other words, the spaced interval between the two conveyer surfaces as they forcibly eject the sand from the device is 55 less than the spaced interval between the surfaces as they converge after passing over their respective upper pulleys, *i. e.*, the points at which the sand is fed from the hopper. Being closer together at the lower 60 pulleys, one of these pulleys is preferably mounted so that it is resiliently held in its adjusted spaced relation. The shaft 32 of the lower pulley 24 is carried in bearing boxes 34, similar to the bearing boxes of the

adjacent lower pulley 8. These bearing 65 boxes 34 are mounted in the forked ends 35 of two legs 36 which are apertured at their upper ends to receive therethrough the shaft 25 of the upper pulley 23. These two legs are substantially suspended from the shaft 70 25 and the two opposed legs 36 are therefore arcuately movable. In order that the lower pulley may be held in the desired spaced relation to the adjacent pulley, a spacing means is provided on each side of 75 the legs 36. These spacing means are alike, and but one is necessary therefore to be described. A rod 37 is terminally affixed to each frame leg. Each rod has an intermediate threaded portion upon which is received in threaded engagement a nut 38. A boss 39 is formed on the leg 36 and is adapted to receive the rod 37 therethrough with a running fit. A spring 40 is coiled about the rod and abuts at one end against 80 this boss 39 and abuts at its outer end against a washer 41 held on the outer threaded portion of the rod by means of the nut 42. The tension of the spring, resistant to movement of the pulley, may be readily 85 adjusted by movement of the nut 42.

Means are provided to prevent the escape of sand transversely of the two conveyers. To this end the longitudinal edges of the opposed working surfaces of the conveyers 90 are substantially closed. This is preferably effected by the guards formed of sheet metal. One pair of guard members 44 is carried by the frame 2 and legs 3 and 4, being secured thereto by screws 45. These guard members 95 100 44 are provided with offset portions 46 (see Fig. 2) along their inner longitudinal edges adjacent the space between the opposed conveyer faces. The guard members 47 are similarly secured by screws 48 to the legs 36 105 and their inner longitudinal edges extend beneath the offset portions 46. The outer edge portions of all guard members extend beyond the edge portions of the conveyers in 110 order to protect the operatives from the moving parts of the device and to provide a means for attachment of the usual safety appliances in accordance with Federal and State laws.

In order that the opposed working surfaces of the conveyers may not recede from each other a backing plate 49 is mounted behind each conveyer so that the conveyer surfaces cannot, during working travel, separate more than the spaced interval predetermined by the two opposed backing plates 49. These plates are secured, as shown in Fig. 4, by means of the angle brackets 50 to the respectively adjacent guards.

This device is preferably operated in a 115 perpendicular position and is adapted to be moved over a flask 51, diagrammatically indicated in Fig. 4, forcibly to project the

packing sand therein. Sand is conveyed to the hopper and is fed by gravity between the conveyers which are preferably actuated, as by electric motors, so that one conveyer is 5 moving relatively to the other. When one conveyer travels at a greater linear rate of speed than the other, a frictional action is produced which functions to reduce lumps in the packing sand before it is forcibly projected from the device to the flask. The 10 resilient mounting of the lower pulley 24 of the conveyer 22 permits the passage of unproduced objects without injury to the device.

There is thus provided a novel, efficient 15 and high-speed sand-packing device which is easy to operate and is of simple and inexpensive construction and may be efficiently operated by others than the highly skilled sand-molders.

Having thus described our invention, what 20 we claim as new and desire to secure by Letters Patent is:

1. A sand-packing device including opposed conveyer members coöperable to project sand fed therebetween, one of which members is movable relative to the other whereby sand lumps may be reduced before projection, and means to actuate said mov-

able member whereby the sand is forcibly projected. 30

2. A sand-packing device including a pair of movable, opposed conveyer members coöperable to project sand fed therebetween into a molding flask, and means to actuate said members at increasing speeds during 35 sand projection whereby sand is more firmly packed in said flask toward the end of a given operation than at the beginning.

3. A sand-packing device including a pair of movable conveyer members having adjacent opposed surfaces adapted to move in the same direction and coöperable to project sand fed therebetween, and means to actuate both said members, one of which members is actuatable at a greater rate of 45 speed than the other whereby sand lumps may be frictionally reduced before projection.

In witness whereof, we have hereunto set our hands this 16th day of June, 1920.

LARS MAGNUS ANDERSON,
AUGUST G. ANDERSON.
